CLAIM

The ornamental design of a display screen with graphical user interface for a penny auction, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen with graphical user interface for a penny auction, embodying the design of the present invention.

The broken lines illustrate the display screen and form no part of the claimed design. The broken lines illustrate portions of the graphical user interface and form no part of the claimed design.
